UNITED STATES PATENT OFFICE.

ADOLPH PETZOLD, OF PHILADELPHIA, PENNSYLVANIA, ASSIGNOR TO
JOHN BROMLEY & SONS, OF SAME PLACE.

DESIGN FOR A RUG.

SPECIFICATION forming part of Design No. 34,555, dated May 21, 1901.

Application filed April 19, 1901. Serial No. 56,669. Term of patent 3½ years.

To all whom it may concern:

Be it known that I, ADOLPH PETZOLD, a citizen of the United States, residing at the city of Philadelphia, State of Pennsylvania, have 5 invented and produced a certain new and original Design for a Rug, of which the following is a full, clear, and exact description, reference being had to the accompanying drawing, forming a part of this specification.

10 My invention relates to the surface ornamentation of a rug. As shown in the accompanying drawing, in which it is seen applied to a woven Smyrna rug, it presents a rectangular pattern or design composed of an outer narrow border A, within the same an inner rectangular line-border B, and between each of these a series of figures composed of parts 15 a and b. Within the field center is a line-fig-

ure C, composed of two parallel straight sides with opposite angular ends, and within this 20 field-center line-figure C is a central figure D, and, finally, within the space between the line-figures B and C is a groundwork-pattern E, composed mainly of connected linework interspersed with small figures. 25

I claim—

The design for a rug substantially as shown and described.

In testimony whereof I have hereunto affixed my signature this 15th day of April, 30 A. D. 1901.

ADOLPH PETZOLD.
